UNITED STATES PATENT OFFICE.

THOMAS H. JACOB, OF WAUSAU, WISCONSIN, ASSIGNOR TO DANIELSON TOOL CO., OF WAUSAU, WISCONSIN.

PINION PULLER.

Application filed December 16, 1919. Serial No. 345,208.

To all whom it may concern:

Be it known that I, THOMAS H. JACOB, a citizen of the United States, and resident of Wausau, in the county of Marathon and 5 State of Wisconsin, have invented certain new and useful Improvements in Pinion Pullers; and I do hereby declare that the following is a full, clear, and exact description thereof.

10 My invention relates to new and useful improvements in means for removing pinions or other members from shafts on which they are keyed or otherwise secured.

It is in general the object of my invention to simplify and otherwise improve the structure and to increase the efficiency and convenience of manipulation of devices of this character.

15 It is more particularly my object to provide a pulling device which in operation exerts an even pressure upon circumferential portions of the member to be withdrawn, and which is provided with a bearing connection for the shaft on which the member 20 is mounted, to insure such even distribution of pressure.

A further object resides in the provision 25 of a puller device for pinions which may be operatively associated therewith by placing the body of the device over the pinion and then partially rotating said body to procure 30 interlocking relation of the pinion teeth with portions of the body.

With the above and other objects and advantages in view, which will be apparent as 35 the description proceeds, my invention resides in the novel features of construction, combination and arrangement of the parts as hereinafter described and defined by the 40 appended claim.

In the accompanying drawings:

Figure 1 is an end view of my improved 45 pinion pulling device with a pinion disposed therein, a portion of the device being broken away.

Figure 2 is a sectional view through the device and pinion.

Referring now more particularly to the drawings, the body member of my improved 50 pinion pulling device comprises in the present instance a cylindrical block 5 having a recess 6 formed in one end and adapted to receive a pinion *p* or other member which it

would be desired to withdraw or remove from a shaft *s* on which said member is secured by a key *k*. The block is provided with an axial bore 7 therethrough communicating with the recess, the inner portion of said bore having a plain surface, while the outer portion of the bore is threaded for the reception of a pressure screw 8 having a turning head 9 on its outer end and having its inner end reduced and unthreaded to provide an abutment head 10 for engagement with the end of the shaft *s*.

For securing a pinion in the recess 6, an inwardly extending annular flange 11 is provided at the mouth of the recess and is provided with an annular series of passages 12 for the teeth of the pinion whereby, when the teeth have been passed through the flange into the recess, and the block or pinion partly turned, each of said teeth may have a firm seating engagement with the flange. The limit of rotating movement to procure 75 this seating engagement is determined by a pin 13 projecting inwardly from the wall of the recess for abutment with one of the pinion teeth. Thus to pull or remove the pinion *p* from the shaft *s*, it is merely necessary to mount the block 5 on the pinion with said pinion disposed in its recess, and then partially turn one of the members and then rotate the screw 9 to exert pressure on the end of the shaft *s*, which has entered the 80 bore 7 when the pinion is engaged in the recess and which consequently affords a bearing for the block 5 and holds same centered with respect to the pinion whereby an even withdrawing pressure is exerted on all of 85 the teeth of the pinion thus increasing the effective strength of the device by a uniform distribution of stress in its operation.

It will be noted that in the operation of my improved puller, when the screw 8 is rotated 90 to pull on the pinion its frictional engagement with the body member 5 will have a tendency to rotate the latter, and will consequently urge the pin 13 firmly against the pinion tooth on which it engages and therefore hold the teeth of the puller in proper 100 position in relation to the teeth of the pinion.

While I have shown and described a preferred embodiment of my invention, it will be appreciated that various changes and 105 modifications of structure may be employed

to meet differing conditions of use and manufacture, without departing in any manner from the spirit of my invention.

What is claimed is:

- 5 A removing device of the class described comprising a hollow member adapted to receive a shaft carried pinion therein, inwardly extending teeth upon said member between which the teeth of the pinion can pass,
- 10 said hollow member being partially rotatable on said pinion, an abutment pin on said hollow member and engageable with one of the

pinion teeth to limit the rotation to a position where the teeth of the body member are behind the pinion teeth, and means carried by the body member for exerting pressure on the shaft of the pinion and simultaneously urging the pin against a tooth of the pinion.

In testimony that I claim the foregoing I have hereunto set my hand at Wausau, in the county of Marathon and State of Wisconsin.

THOMAS H. JACOB.
